BAILER

Wilson Tarkington, Houston, Tex., assignor of
one-half to Sam J. Lucia, Emmanuel M. Lucia,
and John Matranga, all of Houston, Tex.

Application March 5, 1934, Serial No. 713,995

1 Claim. (Cl. 166—19)

My invention relates to improvements in pressure bailers which are usually constructed with a closed top provided with a relief valve, a casing, and a foot valve designed to permit the bailer to contact bottom of the oil well with only atmospheric pressure within the casing, and to load by means of fluid pressure and retain the load. This type of bailer is effective only in wells containing a fluid head, where the fluid well pressure may be utilized to effect the loading of the bailer.

A further object of my invention is to provide a foot valve capable of pulverizing sand, shale, or other obstructions in oil well liners and to open simultaneously with the impact of the bailer admitting to the bailer casing a charge of the sand or other material to be bailed. Also to effectively close the foot valve on suspension of its lower end and hold such charge when the bailer is being withdrawn from the well. A further object is to provide a bailer of this type with a foot valve made of very few parts and at a low cost. Further objects of my invention appear elsewhere in the specification.

Figure 1 shows a combination of the essential parts of the oil well bailer. Figure 2 shows a larger view of that part of the oil well bailer indicated as Section A, Figure 1. Figure 3 is a bottom view of Figure 2. Figure 4 is a top view of Figure 2. Figure 5 is a sectional side view of Section B, Figure 1.

Reference is here made to Figure 1 showing the component parts of the oil well bailer which comprise a sectional casing, indicated by the numeral 3, couplings 4 and 5 between the sections, a top 2, and a foot valve indicated as Section A. The top is attached to casing 3 by threads and collar and provided with a bail to which is attached a cable as a means of lowering into and withdrawing the oil well bailer from the well. The casing 3 is usually in jointed sections and is usually utilized from the oil well pump casing used in connection with the well. The top 2 is provided with a longitudinal passage 27a into the upper end of which a relief valve is threaded 35 secured, as shown more fully in Figure 5. Figure 2 shows a sectional view of a foot valve which is threaded into the lower end of casing 3 by coupling 5, the valve being shown in its closed position. In the valve a cylindrical element 6 is telescopically mounted within the packing nut 7 and element 8. The downward movement of element 6 into element 8 is adapted to telescope sleeve valve members 9 and 10 to register three valve ports 12 formed in an inner valve member 9 which is secured in the lower end of cylinder 6,

with the corresponding three valve ports 15, in outer sleeve valve member 10 attached to outer cylinder 8. This telescoping movement opens the foot valve permitting ingress of sand or other material into casing 3 to be trapped and withdrawn from the well.

The outer valve member 10 is threaded concentrically into a circular opening 18a in the lower end of element 6 at 18. Inner valve member 9 is threaded concentrically of the member 10 within the circular opening 17a in partition 17 within outer cylinder 8. Inner valve member 9 is open at both ends and slides closely within outer valve member 10, and is substantially fluid-tight when ports 12 and 15 are not registered or open. Inner valve member 9 is usually constructed of bronze casting to prevent sticking or corroding. The valve ports in members 9 and 10 are held in exact longitudinal alignment by means of a key 13, Figure 4, which may be set into any one of the grooves 19, 20, 21, 22, and 23 which are cut into collar 24.

The relief valve shown in Figure 5 consists of a cage 31, a set screw 27, a valve seat 30, a bakelite valve disc 29, and a spring 28, which are situated in the top as shown in the drawing. Numeral 26 shows a small perforated nipple closed at its lower end and threaded into the bore hole 27—A. The object of placing this perforated nipple 26 is to provide multiplied means of outlet of high pressure should one or more of the holes become stopped with débris.

The whole combination is attached to a wire line as means of lowering into and withdrawing from the oil well. It is essential that the well bore contain a head of fluid for the successful operation of the bailer. The bailer is lowered into the well bore and descends through the fluid head until the matter to be bailed is encountered, and the lower end of element 8 is suddenly stopped, causing a relatively upward movement of element 8 to the bailer casing. In other words, the weight of casing 3 causes a sudden telescoping of Section A, registering the valve ports in members 9 and 10. The fluid being excluded from the combination in its movement downward until the matter to be bailed is encountered by the lower end of element 8, permits the combination to descend with only atmospheric pressure within the casing, through the fluid head, until the matter to be bailed is contacted by the lower end of element 8 and is in close proximity to the ports of the foot valve, Figure 2. The opening of the ports in the foot valve, Figure 2, admits a dynamic ingress of fluid, sand, or shale, into casing 3,

until the pressure within the casing 3 is equalized with the well bore fluid pressure. When the combination is moved upwardly relatively to the well bore by means of the wire cable, element 8 is again suspended, consequently the valve ports in members 9 and 10 are closed by the suspended weight of element 8, and the material trapped within the casing may be withdrawn from the well. Upon withdrawal from the well mouth the contents of the bailer are dynamically discharged by permitting element 8, under the weight of casing 3, to come to rest upon any solid object at or below the derrick floor. When the combination is again suspended perpendicularly, the weight of element 8 again closes the valve ports in members 9 and 10, and the bailer is ready for a repeat operation.

The relief valve shown in Figure 5 is regulated by set screw 27 to retain a light pressure within the bailer above atmospheric pressure for the successful discharge of the contents of the bailer at the derrick floor. This valve also assists in the loading of the bailer at the bottom of the bore hole, as when element 8 contacts the material to be bailed, the in-rush of fluid, sand, or other matter, at a greater pressure than the pressure at the bailer top will effect the discharge of most of the air contained in the bailer casing 3 into the fluid head of the well.

The embodiment of my invention as described is only a preferred one and I do not wish to be restricted in its practice or limited in the claim thereof.

What I claim is:

In a bailer for bailing oil wells having fluid head pressure, the combination of a casing closed at its upper end by means of a top provided with a bail for attaching a cable as means of lowering into and withdrawing from an oil well, said top being provided with a relief valve adjusted to hold sufficient bottom well pressure in the casing to effect unloading at the surface, the casing provided with a foot valve attached to its lowermost end, said foot valve comprising cylindrical telescopic body elements with limited longitudinal movement for the operation of two inner concentric cylindrical slide valve members, the outer element having a partition therein intermediate its ends and the inner element having a bottom wall, the inner slide valve members comprising one inside member open at both ends and secured at its lower end in an opening in said partition, and one outside member closed at its upper end and secured at its lower end in an opening in said bottom wall, ports in each member adapted to register when the cylindrical body elements are telescoped, the foot valve ports opening when said bailer strikes sand, shale or other material of a solid nature within the well bore bottom, to allow ingress of well fluid and other matter to be bailed, and closing when the elevator is elevated to trap the contents within the bailer casing.

WILSON TARKINGTON.
